(57) CLAIM

The ornamental design for a dog toy, as shown and described.

DESCRIPTION

FIG. 1 is a front view drawing of a dog toy, showing my new design, the back view and the side views being the same; and, FIG. 2 is a top view thereof.

The broken lines illustrate environmental structure and form no part of the claimed design.

1 Claim, 2 Drawing Sheets

FIG. 1

FIG. 2
